Primary Examiner — Darcey E Gottschalk

(57) **CLAIM**

The ornamental design for an X-ray device for medical treatment, as shown and described.

DESCRIPTION

1. X-ray device for medical treatment

1.1 : Front

1.2 : Back

1.3 :Top

1.4 : Bottom

1.5 : Left

1.6 : Right

1.7 : Perspective

1.8 : Perspective

1.9 : Enlarged partial view of a portion defined by arrows 1.9 of reproduction 1.8

The dash-dotted broken lines define the bounds of the claimed design; the evenly spaced broken lines show an X-ray device for medical treatment; all broken lines form no part of the claimed design.

1 Claim, 9 Drawing Sheets(56)
